NECKTIE MANUFACTURE

Jack Weisbaum, Cincinnati, Ohio

Application March 5, 1936

5 Claims.

My invention relates to improvements in the step of blocking neckties, and to an improvement in necktie pressing machines which may be used in connection with my new method.

5 In the manufacture of neckties it has been the custom in the past to lay a plurality of plies of material on the cutting table, and in accordance with a predetermined pattern, to cut through a number of successive layers at the same time. This makes a desired number of ties with various kinds of material which may be made up in the same manner, and the ties will accordingly all be the same size.

There are a great many different styles of 15 neckties, both of the four-in-hand and bow type, and there are various plans of folding the material and inserting linings in the ties.

The silk or other fabric from which ties are made is usually such that it must be "blocked" 20 before the tie can be made up.

The usual method of blocking a tie in the past has been to place the material on a flat board, and then place on the material a cardboard pattern piece having the finished width and length 25 of the tie. The material is then folded over the pattern piece, and, since the pattern piece must be removed before the tie is finished, it has been customary for the tie maker to take a hand iron and press the edges of the folds of the material 30 along the edges of the pattern piece. The pattern piece is then removed and the liner inserted, if the liner is to be used, and the various folds of the material are stitched together, with the side edges of the tie remaining the pre-creased edges 35 of the original material as set or blocked by the pressing with the hand iron.

The hand blocking of the tie material requires very delicate workmanship, and is a painstaking operation, because the least little crinkle in the 40 fabric, causes the tie to develop twisted portions which are unattractive in appearance and make the ties unsalable.

It is the object of my invention to provide a greatly simplified method of mechanically blocking the tie by a pressing operation which obviates the necessity of using a pattern piece and any hand iron pressing of the material along pre-determined fold lines.

It is further my object to provide in combination with a pressing machine, a series of pattern pressing plates which will enable a tie maker to press the tie material and then proceed with the finishing of the tie without further manipulation of the material.

55 The above objects and other objects to which

reference will be made I have illustrated in the following drawing and description with reference to a four-fold tie, in which the edges of the fabric are folded in and lie along one edge of the tie so that the tie may be pressed without developing a shiny line along the lines of fold of the edges of the material.

In a three-fold tie the cut edges of the fabric are folded in so that they lie along a medial line extending longitudinally through the tie, and in pressing such a tie there is an uneven thickness of plies of material which cause a shiny line to develop corresponding to the meeting edges of the fabric of which the tie is made.

Referring to the drawing,

Fig. 1 is a lateral sectional view of a pressing machine having a head and buck equipped with pattern plates for pre-creasing the material along pre-determined lines.

Fig. 2 is an elevation of the upper pressing head as it would be viewed along the lines 2, 2 in Fig. 1.

Fig. 3 is a plan view of the buck-pattern plate in the pressing machine shown in Fig. 1.

Fig. 4 is a plan view of a tie which is pre-creased along pre-determined lines for forming a four-fold tie.

Fig. 5 is a perspective view of the four-fold tie shown in Fig. 4, after the finishing operation.

The pressing machine shown has a head 1 which may be operated by means of a handle 2 to descend against the buck 3. The head is equipped with a pattern plate 4 having a series of pattern ridges 5 formed in the plate, through which a series of openings 6 extend so that, if desired, steam may be admitted to the hollow interior of the pressing head and pass through the openings along the ridges in the upper pattern plate. The buck has a pattern plate 7, with grooves 8 therein corresponding to the ridges 5 in the upper pattern plate, and perforations 9 may be provided which extend from the hollow interior of the buck so that steam may be caused to issue from the perforations along the lines of the grooves.

As indicated in Fig. 1, the pattern plate 7 is mounted in the buck so that the peripheral edges of the pattern plate are recessed below the surface of the buck so that the tie blank, as illustrated in Fig. 4, may be positioned on the buck and in the recess, shown in Fig. 3, prior to the pressing operation. The recessed peripheral edges assist the operator in locating and positioning the blank relative to the creasing pattern plates. The tie blank fits snugly in the recess in the buck and because of the peripheral

edges of the recessed portion there will be no tendency for the blank to become disaligned. I consider this positioning and locating operation an essential step in my process because the tie blank is of flimsy material and without accurate positioning and locating the creases would not be formed in the blank along the proper lines. Without accuracy in the arrangement of the creases in the tie blank the making of a perfect tie cannot be accomplished. Thus my method not only obviates a great deal of work on the part of the operator but insures uniform production so that one tie will be exactly like every other tie.

In packing and displaying ties that each tie should be exactly like every other tie is a very important matter, and one of the reasons why my method has led to such commercial success is because purchasers come to know that each tie will be exactly like every other tie regardless, of course, of the difference in pattern of the material from which the tie is made.

The press may otherwise be equipped in the usual manner so that open steam may be caused to issue through the perforations in the upper and lower pattern plate at desired intervals, or so that a vacuum may be induced in either the head or the buck. It may further be desired to have a connection so that air pressure may be induced in either the head or the buck.

Referring now to Fig. 4, the tie material generally indicated at 10 has diagonally cut ends 11, 11a, the end 11a being the portion which is larger and will accordingly be the outside, visible portion of a four-in-hand tie. It will be noted that the tie has three lines of fold or creases ab, cd, and ef, which are caused by the creasing of the fabric between the ridges a'b', c'd' and e'f' of the head pattern plate, and the grooves a²b², c²d², and e²f² of the buck pattern plate.

After the fabric has been pressed, the operator first folds down the fabric along the crease ab, and then folds the fabric along the crease ef. The double ply folds are then folded together along the creases cd. This will cause the edges gh of one side of the fabric piece and the edges ij of the other to lie in overlapped parallel arrangement extending along one of the edges of the finished tie as indicated in Fig. 5. The opposite edge of the tie will be formed by overlying layers, the outer layer being the fold along the lines ab, and the underlying folded layer the fold along the line ef, so that when the tie is pressed the entire medial section will be free from any underlying edges or edge folds of fabric, and so that the tie may be pressed without danger of developing a shiny area.

The folding of the blank into the finished tie may be more easily explained by referring to that portion or width of the tie between the creases cd, ab as the first or exposed width; that portion between the crease ab and the side edge gh as the second width; that portion between the creases cd and ef as the third width and that portion between the crease ef and the side edge ij as the fourth width.

While I have described my invention with reference to a four-fold tie, the same plan may be used in blocking a tie composed of any desired number of folds, such as an eight-fold tie.

By the use of my invention, I eliminate entirely the necessity of using cardboard patterns, and the hand pressing of various creases or fold lines during the making of the tie. The folds of the tie remain until such time as the maker wishes to finish the tie, which can be accomplished sim-

ply by the addition of stitches as indicated in Fig. 5 at k and l.

If material such as "Palm Beach" cloth is used as the fabric, and the material is cut on the bias, a four-fold tie can be made without any lining, and with only stitches holding the tie together along the fold lines ef, ab. With such a construction there is no tendency for the tie to pull out of twist at the tie portion, and the tie may be laundered and pressed without it being necessary to remove the stitches which hold the tie together.

Having thus described my invention, what I claim as new and desire to secure by Letters Patent, is:

1. A process of manufacturing four-in-hand ties without a hand blocking operation, which comprises cutting a supply of fabric on the bias to form a long, narrow, irregularly shaped tie blank, positioning said blank with respect to longitudinally disposed crease forming elements and the edges of said blank with respect to longitudinally disposed edge positioning means, said crease forming elements bearing a predetermined spatial relationship to said edge positioning means, and bearing a predetermined spatial relationship each to the other, in such a way that said crease forming elements extend generally in the bias direction of said tie blank and in such a way that the edges of said tie blank bear a predetermined spatial relationship to said crease forming elements throughout the length of said edges, and simultaneously forming in said tie blank by means of said crease forming elements a series of at least three longitudinally disposed non-parallel form retaining creases, said creases being formed from the same side of said tie blank and having predetermined spatial relationship to each other and to the edges of said blank, then folding said blank along the lines of said form retaining creases over and over upon itself to form a tie body, and securing folded portions of said tie body to each other.

2. A process of manufacturing four-in-hand ties without a hand blocking operation, which

comprises cutting a supply of fabric on the bias to form a long, narrow, irregularly shaped tie blank, hemming end portions of said blank, positioning said blank with respect to longitudinally

disposed crease forming elements and the edges of said blank with respect to longitudinally disposed edge positioning means, said crease forming elements bearing a predetermined spatial relationship to said edge positioning means, and bearing a predetermined spatial relationship each to the other, in such a way that said crease forming elements extend generally in the bias direction of said tie blank and in such a way that the edges of said tie blank bear a predetermined spatial relationship to said crease forming ele-

ments throughout the length of said edges, and simultaneously forming in said tie blank by means of said crease forming elements a series of at least three longitudinally disposed non-parallel form retaining creases, said creases being formed from the same side of said tie blank and having predetermined spatial relationship to each other and to the edges of said blank, then folding said blank along the lines of said form retaining creases over and over upon itself to form a tie body, and securing folded portions of said tie body to each other.

3. A process of manufacturing four-in-hand ties without a hand blocking operation, which

comprises cutting a supply of fabric on the bias

- to form a long, narrow, irregularly shaped tie blank, positioning said blank with respect to longitudinally disposed crease forming elements and the edges of said blank with respect to longitudinally disposed edge positioning means, said crease forming elements bearing a predetermined spatial relationship to said edge positioning means, and bearing a predetermined spatial relationship each to the other, in such a way that
- 5 said crease forming elements extend generally in the bias direction of said tie blank and in such a way that the edges of said tie blank bear a predetermined spatial relationship to said crease forming elements throughout the length
- 10 of said edges, and simultaneously forming in said tie blank by means of said crease forming elements a series of at least three longitudinally disposed non-parallel form retaining creases, said creases being formed from the same side of
- 15 said tie blank and having predetermined spatial relationship to each other and to the edges of said blank, then folding said blank along the lines of said form retaining creases over and over upon itself to form a tie body, and securing
- 20 folded portions of said tie body to each other with spaced stitches so arranged between the folds which hold the tie body together, that uniform longitudinal stretchability of the tie will result without buckling of the fabric of the tie
- 25 body.
4. A process of manufacturing four-in-hand ties without a hand blocking operation, which comprises cutting a supply of fabric on the bias to form a long, narrow, irregularly shaped tie
- 30 blank, positioning said tie blank in a correspondingly shaped recess in a pressing surface whereby the edges of said recess serve to position said blank, said recess having a plurality of longitudinally disposed, non-parallel, ridge forming depressions therein bearing a predetermined spatial relationship to each other and to the edges of said depression, and pressing said tie

blank therein by means of a cooperating pressing member characterized by a raised portion of a size and shape similar to said recess, said raised portion having raised ridge forming members thereon of a size, shape and disposition corresponding to the size, shape and disposition of said ridge forming depressions whereby to form in said blank simultaneously a series of at least three longitudinally disposed non-parallel form-retaining creases, then folding said tie blank 10 along the lines of said form-retaining creases over and over upon itself to form a tie body, and securing folded portions of said tie body to each other.

5. A process of manufacturing four-in-hand ties without a hand blocking operation, which comprises cutting a supply of necktie fabric to form a long narrow irregularly shaped tie blank, positioning said blank with respect to longitudinally disposed crease forming elements and the edges of said blank with respect to longitudinally disposed edge positioning means, said crease forming elements bearing a predetermined spatial relationship to said edge positioning means, and bearing a predetermined spatial relationship each to the other, in such a way that said crease forming elements extend generally in alignment with the length of said tie blank and in such a way that edges of said tie blank bear a predetermined spatial relationship to said

15 crease forming elements throughout the length of said edges, and simultaneously forming in said tie blank by means of said crease forming elements, a series of longitudinally disposed non-parallel form retaining creases, said creases having predetermined spatial relationship to each other and to the edges of the blank, then folding said blank along the lines of said form retaining creases to form a tie body, and securing folded

20 portions of said tie body to each other.
